UNITED STATES PATENT OFFICE.

FRANCIS H. GLAHN, OF SOUTH OMAHA, NEBRASKA.

STARTING MECHANISM FOR GAS-ENGINES.

982,133.

Specification of Letters Patent. Patented Jan. 17, 1911.

Application filed May 6, 1910. Serial No. 559,789.

To all whom it may concern:

Be it known that I, FRANCIS H. GLAHN, a citizen of the United States, residing at South Omaha, in the county of Douglas and State of Nebraska, have invented certain new and useful Improvements in Starting Mechanism for Gas-Engines, of which the following is a specification.

This invention relates to starting mechanism for gas engines, and more particularly for use in connection with automobiles; and has for its object, broadly, the provision of means for the storage of a force communicated by a movement of the driving shaft while the engine is in motion, and means for thereafter utilizing this force for the purpose of starting the engine, thereby dispensing with the usual practice of manually cranking the engine when starting it.

In starting an automobile it is generally necessary to perform the operation of "turning the engine" or, in other words, to cause it to move through the aspiring and compression strokes to the point of ignition; and the operation of manually rotating the cranking shaft is quite inconvenient, and when turning the crank of the cranking shaft at the front of the car the operation is frequently attended with danger.

The invention has reference to a structure of few and simple parts, the same to be reliable and automatic in operation, and which may be under convenient control; another object is to provide a starting mechanism which may occupy a limited space within the car.

With these objects in view, the invention discloses a novel combination and arrangement of parts as herein described and claimed, and as illustrated in the drawing, it being understood that changes in form, size, proportion or other minor details may be made within the scope of the claims without departing from the spirit of the invention or sacrificing any of its advantages.

In the accompanying drawing forming a part of the application, Figure 1 is a plan view of a part of an automobile, with the starting mechanism mounted thereon, the recessed disk or barrel and the spiral spring being in section. Fig. 2 is a vertical end view of the barrel, the pinion of the driving shaft also being shown. Fig. 3 is a view of the end of the barrel, being the end opposite to that shown in Fig. 2. Fig. 4 is an en-

larged plan view, partly in section, to clearly illustrate the principal parts shown in Fig. 1. Fig. 5 is a detail relating to Fig. 4, being a side view of the slideable supporting-frame.

Referring now to the drawing for a more particular description, numerals 1 and 2 indicate the respective side plates, and 3 the front end plate of an automobile, these being parts of the car frame.

The driving or crank-shaft is indicated at 4, said shaft having pinion 5 mounted upon its front terminal.

At 6 is indicated a cross bar, the same being a part of the car frame; it is suitably mounted upon and extends between side plates 1 and 2.

At 7 is shown a slideable supporting-frame, the same being mounted upon cross bar 6, said frame being provided with oppositely disposed, longitudinal engaging plates 8 adapted to have seatings inclosingly upon the sides of member 6.

At 9 is indicated a cranking-shaft, the same being disposed substantially parallel with the driving shaft, and having one of its ends mounted in suitable bearings 29 upon and midway between the ends of frame 7, its front end extending in a direction of the forward part of the car.

At 10 is indicated a rotatable, vertically-disposed disk or barrel, the same being keyed upon shaft 9 and provided with the internal gear 11 formed in its rear end, its front end having formed therein the endless groove or trackway 13, best shown in Fig. 3, said trackway being arcuate in form and comprising the outer and inner portions respectively indicated at 14 and 15.

At 16, best shown in Fig. 2, is indicated a toothed cylinder preferably formed integral with the barrel and disposed at the middle of the rear end thereof, and at 17 intermediate this toothed cylinder and the internal gear 11 is provided the concaved gear portion 17 which forms a connection between gears 11 and 16.

At 30 is indicated a concaved portion disposed opposite to portion 17, the degree of curvature thereof being the same as the curvature of concaved portion 17; it is provided with teeth the same as portion 17 except an intermediate blank portion 31 is provided, as clearly shown in Fig. 2, and the geared portions of the barrel thus described provide a continuous gear with the

exception of blank portion 31. The disk or barrel thus described may be conveniently cast as an integral structure.

One of the junctions of the outer and inner arcuate grooves 14 and 15 is indicated at 18, best shown in Fig. 3. At 19, adjacent to junction 18, is shown the opposite junction of these grooves. It will be seen that junction 18 of the grooves and the concaved gear portion 17 are disposed opposite to each other upon opposite ends of the barrel; and junction 19 of the groove is disposed similarly with reference to concaved portion 30. A recess 20 is formed at junction 19, said recess communicating with grooves 14 and 15. While this recess is upon an end of the disk opposite to the blank portion 31, it may be said to be adjacent to said blank portion and it forms a pocket or depression extending in a direction opposed to said blank portion, and it is disposed between said grooves.

At 21 is indicated a roller having a stem mounted upon plate 3 adjacent to and at the front of the disk, and said roller is adapted to have a seating at all times either in recess 20 or in one of the trackways 14 or 15.

At 22 is indicated a spiral spring, its inner end 23 being mounted upon the periphery of the barrel, its outer end 24 being mounted upon arm 25 of frame 7. Pinion 5 of the crank shaft has a diameter less than the distance between the internal gear and the gear of cylindrical portion 16 of the barrel, and said pinion is normally disposed adjacent to and between these gears and out of engagement therewith. The crank shaft rotates in the direction indicated by the small arrow in Fig. 2. Since the barrel is mounted upon the slidable supporting-frame 7 it may have a movement transversely of the car. For the purpose of moving frame 7 transversely of the car any suitable means may be employed, the means herein shown being the strand 26 having its inner end mounted at 27 upon one of the ends of said frame, the strand being supported by pulley 28.

It has been stated that roller 21 is normally disposed within recess 20. At this time, as will be seen, the spring is completely coiled or wound. It will be understood that at this time pinion 5 is disposed in the position shown in Fig. 2, and is not engaged by any of the gears of the disk. Since pinion 5 of the crank shaft is normally disposed adjacent to the toothed parts of concave portion 30, a limited movement of the slidable supporting-frame in a direction of side plate 1 of the car will cause engagement of said pinion 5 with the cylindrical gear 16. The parts are so arranged that while roller 21 is seated in the inner curved groove 15, pinion 5 will engage cylindrical gear 16; and when the roller is

disposed in the outer groove 14 the pinion will engage the internal gear 11.

From the description, the operation of starting the car and the winding of the spring will be readily understood. To start the engine, frame 7 is moved a limited distance in a direction of side plate 1 by use of strand 26; this movement will change the seating of roller 21 from recess 20 to the inner groove 15; the spring thereupon will be released and will cause the disk to rotate in the direction of the large arrow in Fig. 2; pinion 5 thereupon will be engaged by the cylindrical gear 16 and said pinion will be rotated in a normal direction by force of the spring; in other words, the release of the spring will cause a rotatable movement of the disk in the direction of the arrow last mentioned and will cause gear 16 to actuate said pinion.

When pinion 5 is engaged by cylindrical gear 16 as last described, the crank shaft will be moved substantially a single revolution but this is sufficient for the purpose of starting the engine and car, since it causes the engine to pass the ignition point, and a continued rotatable movement of the crank shaft will follow in the usual manner.

The operation of winding the spring is automatic. It becomes wound immediately after the first revolution of the crank shaft, by reason of the reverse movement of the disk, as will be explained.

The slidable frame has two movements; its first movement has already been mentioned in connection with the starting of the engine.

The disk has two revoluble movements. It is moved substantially one revolution by force of the spring as already described. At the time its revolution has been completed roller 21 will be seated at junction 18 of grooves 14 and 15, and at that time concaved gear portion 17 will be in engagement with the pinion. At this time the pinion 5 of crank shaft 4, being thus actuated by the engine, will cause a reverse rotatable movement of the disk, for the reason that said pinion is then in engagement with gear 11, roller 21 being disposed within groove 14; and the reverse rotatable movement of the disk will continue until the roller 21 reaches recess 20 at junction 19 of the grooves, at which time said roller becomes seated in said recess and pinion 5 is free from engagement with the gears. During the reversely rotatable movement of the disk, the slidable supporting frame will be moved in a direction of side plate 2 of the car to its normal position. The second or reversely rotatable movement of the disk, referred to, immediately follows its first rotatable movement and the spring becomes wound immediately after it has spent its energy. The first revoluble movement of the disk is

caused by the spring and its second movement is caused by the engine; and the spring remains wound at all times except when temporarily released to start the engine and 5 car.

While I have shown and described a disk having an arcuate recess in one of its ends the walls of the recess being formed as a gear, the opposite side being formed with 10 the arcuate grooves mentioned, it is obvious that other members or structures could be provided, the same having adjacent rack bars as a substitute for the arcuate recesses with toothed walls, means being provided 15 for guiding the movements of such member so that it will present one of these rack bars contactingly with the teeth of the pinion to actuate the latter in one direction, the member being moved in an opposite direction 20 by action of the pinion when in engagement with the opposite rack bar, and I do not limit myself to the use of the disk or barrel since the elements mentioned would be identical in operation.

Having described my invention, what I 25 claim and desire to secure by Letters Patent is,—

1. A starting mechanism for gas engines, comprising, in combination with a driving 30 shaft having a pinion thereon, a spring-actuated disk-member suitably mounted for rotation and provided near its periphery with an arcuate geared portion and formed at its middle with a substantially cylindrical 35 geared portion; means to cause engagement in alternation of the pinion with the gear of the cylindrical portion and the gear of the arcuate portion; and means to dispose the disk with its geared portions out of engagement with said pinion.

2. A starting mechanism for gas engines, comprising, in combination with a driving 40 shaft having a pinion thereon; a pivotally mounted disk member having a middle portion provided with a substantially cylin-

drical gear and formed near its periphery with an arcuate geared portion; a spiral spring carried by said disk; means to cause engagement of the gear of the cylindrical portion with the pinion, said pinion being 50 thereby rotated in one direction by operation of said spring; and means to subsequently cause engagement of the gear of the arcuate portion with said pinion, thereby causing a rotation of the disk in a reverse direction and causing actuation of the spring; and means to dispose the disk with its geared portions in disengagement with said pinion.

3. In starting mechanism for gas engines, 55 the combination of a frame having a support movably mounted thereon, a driving shaft provided with a pinion, a disk pivotally mounted upon the movable support and having an arcuate recess formed in one of its ends, the walls of said recess being provided with a gear and a blank portion, the opposite end of said disk being formed with a connected outer and inner arcuate groove provided with a recess disposed adjacent to 60 the blank portion of said arcuate recess, a roller mounted upon the frame and normally seated in the recess of said groove; resilient means to cause a revoluble movement of the disk in one direction for actuating 65 said driving shaft, the roller being disposed within the inner groove and causing engagement of the pinion with one portion of said gear during such revoluble movement, the disk being rotated in the opposite 70 direction by actuation of the driving shaft, said roller being then disposed within the outer groove to cause engagement of the 75 pinion with another portion of said gear.

In testimony whereof I have affixed my 80 signature in presence of two witnesses.

FRANCIS H. GLAHN.
